UNITED STATES PATENT OFFICE.

WALTER AUDAER WILSON, OF ARMLEY, LEEDS, ENGLAND.

MOLD.

Application filed January 2, 1920. Serial No. 348,838.

(GRANTED UNDER THE PROVISIONS OF THE ACT OF MARCH 3, 1921, 41 STAT. L., 1313.)

To all whom it may concern:

Be it known that I, WALTER AUDAER WILSON, a subject of the King of Great Britain, residing in Armley, Leeds, in the county of 5 York, Great Britain, have invented certain Improvements in Molds (for which I have filed application in Great Britain Apr. 3, 1915, No. 5,119), of which the following is a specification.

10 This invention relates to means for manufacturing radiants or "fuel", so called, used in gas fires.

In constructing radiants for gas fires, which radiants are generally made from a 15 suitable clay, or other material, the usual method has been to make a radiant in halves, which are joined together before being burned in a kiln. This method has its advantages in that roughness, ribs, projections, 20 studs, or the like, can be readily constructed, or formed, on the interior of the radiant. In other cases, the radiant has been made in one piece on one or more center pins, which gave a stronger construction, but did not 25 permit studs to be formed on the inside. When roughness, or any projection, was desired, it usually took the form of continuous ribs, as the withdrawing of the center pin did not break the continuity of the ribs.

30 After considerable experiment, I have found that a radiant provided (in the preferably solid back) with studs, nipples, or pointed projections, is more efficient than ribs, although lateral ribs, as against vertical ribs, may be employed.

I have also found that the highest efficiency is attained with projections, or the like, increasing in size, i. e., as to distance, they project into the interior of the radiant 35 as they get farther away from the burner.

40 My object is, therefore, to devise means to enable me to construct a radiant in one piece without joints, the construction being that hereinbefore described as a result of my experiments, such means permitting of 45 one or several columns of "fuel" in one piece, whether such radiant be straight or curved.

In describing my invention in detail, reference is made to the accompanying sheets 50 of drawings, in which:

Fig. 1 represents a sectional elevation of

a mold adapted to make a curved radiant with my improvement added thereto;

Fig. 2 is a side elevation of the molds with the plates in position; 55

Fig. 3 is a plan view of the center plate having depressions;

Fig. 3^a is an edge view of the plate shown in Fig. 3;

Fig. 4 is a plan view of the locking 60 plate;

Fig. 4^a is a side view of the locking plate; and

Fig. 5 is an end view of the two molds and 65 plates in position.

In carrying my invention into effect, I will describe and will show the same as applied to a curved radiant of three sections, the curve naturally presenting more difficulties than a straight one. I wish it to 70 be understood, however, that I may apply my invention to straight or curved radiants, whether in single or multiple form. I may also vary the method of operating the molds and center plates as long as there is 75 present the plurality of center plates with suitable molds.

In the first place, I employ what I term a "face mold A", in which is formed any suitable pattern. On this mold is laid a suitable thickness of clay, or other suitable material. On the clay, or like, is placed the locking plate C, which is of a suitable thickness. Over this plate is placed another plate C', which has its uppermost face provided 85 with a series of depressions, or longitudinal cuts, P, of suitable configuration, and, where desired, of varying depth, or size. Over this plate C' is placed another layer of clay, or the like, and the mold is completed 90 by the back mold A', which may be constructed to give a perforated, semi-perforated, or solid, back, as desired. The plates C and C' have suitable handles, and a space is left between the two molds 95 for the handles to project. The other, or outer, ends may project through a similar aperture, or space, in the other, or opposite, side of the molds.

The shoulders of the plates are held 100 firmly in position within the molds by suitable means, such as blocks, or stops. In the

form shown, the locking plate C has a shoulder C⁴ formed to receive the shoulder of the center plate C'. The blocks, or stops, may bear against the outer portion of such shoulder.

Pressure is then applied to the mold and the "fuel" is thereby formed in one piece of clay to be kilned after drying. The locking plate C, the shoulder-retaining device having been removed, is then withdrawn from under the projection center plate C', which allows said plate to drop, or be moved, into the space previously occupied by the locking plate C, leaving the projections formed in the back of the radiant. The center plate C' is withdrawn in the same manner as the locking plate C without disturbing the projections.

The means, hereinbefore described, permit me to make a radiant in one piece, said radiant having suitable projections on the back as opposed to vertical ribs. The radiant may be made straight or curved, the molds and the plates being constructed to suit.

In the form shown, the plates and molds are adapted to form three columns of "fuel" in one piece, divisions C² and C³ being formed in the plates C and C' for the reception of the clay to form side, or division walls. As it is desirable to form the division walls of the "fuel" I provide, in the molds, suitable upstanding projections, such as B, which are adapted to enter the divisions C² and C³ and so form the desired gaps.

To insure the plates taking the correct position in the mold during pressure, I extend the ends C⁴ and C⁵ of the plates C and C', as shown. I also provide upstanding, or depending, guides D in the molds (Fig. 5). The projections B serve, to some extent, to insure the plates taking their correct positions. When desired, projection center plates may be employed on each side of the locking plate, and the radiants may have

projections on the inside faces of both the back and the front.

I wish it to be understood that I may vary the form of projections, or lateral ribs, without departing from the essential features of the invention, and I do not confine myself to any particular pattern of radiant, or form of mold for same. I may vary the arrangement of molds as long as I employ the locking plate and projection plate, or plates.

I claim:

1. In the manufacture of jointless radiants, the combination of a face mold; a back mold; projections on one of said molds; and two plates located between said molds, one of said plates having a series of depressions, both plates being slotted longitudinally to receive the projections of the mold, so that one plate after the other can be removed from the mold after the radiant has been cast.

2. In the manufacture of jointless radiants, the combination of a face mold and a back mold; two plates located side by side and between the two molds, each plate being slotted longitudinally, one of said plates having depressions, the molds having projections extending into the slots; and means for locking the molds and plate in alignment, the plates being so formed that one plate after the other can be removed from the space between the molds.

3. The combination of a face mold; a back mold; the opposed faces of the molds being curved; projections on one of said molds; and two curved plates located between the molds, one of said plates having a series of depressions, both plates being slotted to receive the projections of the mold so that one plate after the other can be removed from the space between the molds after the article has been cast.

WALTER AUDAER WILSON
